TRAPEZOIDAL CAVITY MAGNETRON

Filed Oct. 15, 1942

UNITED STATES PATENT OFFICE

2,520,955

TRAPEZOIDAL CAVITY MAGNETRON

Ernest C. Okress and Ilia E. Mouromtseff, Montclair, N. J., assignors to Westinghouse Electric Corporation, East Pittsburgh, Pa., a corporation of Pennsylvania

Application October 15, 1942, Serial No. 462,132

4 Claims. (Cl. 250—27.5)

1

This invention relates to generators of high frequency electricity, and particularly those of the type called magnetrons.

The principal object of our invention, generally considered, is an improved magnetron for energy in the region of 10 centimeter wavelengths and a method of manufacture.

Another object of our invention is the manufacture of magnetrons by a method which avoids the necessity of very accurate machining.

A further object of our invention is to simplify and cheapen the construction of magnetrons.

A still further object of our invention is to increase the permissive tolerances in the manufacture of magnetrons.

Other objects and advantages of the invention, relating to the particular arrangement and construction of the various parts, will become apparent as the description proceeds.

Referring to the drawings—

Fig. 1 is a sectional view on the line I—I of Fig. 2, in the direction of the arrows, with parts in elevation, of a magnetron embodying our invention.

Fig. 2 is a perspective view on the line II—II of Fig. 1, in the direction of the arrows, with parts in elevation.

Fig. 3 is a sectional perspective view of a blank which is desirably used in manufacturing the body member of the magnetron.

Fig. 4 is a perspective view of one of the partition elements of a magnetron embodying our invention.

Fig. 5 is a fragmentary view corresponding to Fig. 1 but showing a modification.

As pointed out in the Okress application, Serial No. 460,376, filed October 1, 1942, and owned by the assignee of the present application, resonant cavity magnetrons, such as those in the 10 centimeter range, have previously been constructed as there illustrated in Fig. 12, that is, with generally cylindrical cavities disposed about a central pocket adapted to receive the cathode and communicating therewith.

In said application it is shown how accurate machining may be avoided by a modified construction in which slots took the place of the generally cylindrical cavities, three forms being there disclosed; first, in which the slots were of generally uniform width and separated by partitions generally trapezoidal or sector shaped in section on a plane perpendicular to the axis; second, in which said slots were generally trapezoidal or sector shaped and separated by generally trapezoidal or sector shaped partitions; and

2

third, in which said slots are generally trapezoidal or sector shaped and separated by relatively thin partitions or such generally rectangular in section. It is also shown that such improved constructions resulted, not only in avoiding accurate machining but also in substantially reducing the wavelength sensitivity.

In accordance with the present invention we have devised an improved construction of magnetrons with generally trapezoidal or sector shaped cavities, as well as an improved method of manufacture.

Referring to the drawings in detail, and first considering the embodiment of our invention illustrated in Figs. 1 and 2, there is illustrated a magnetron 11 comprising a housing body or anode portion 12 of oxygen-free, high-conductivity copper having relatively thin, that is, considerably thinner than the radial thickness of said body 12, plates or vanes 13, 14, 15, 16, 17, 18, 19 and 20 preferably formed of selenium copper alloy (described by Smith in A. I. M. and M. E. Tech. Pub. No. 870) which plates define generally triangular, trapezoidal or sector shaped pockets 21, 22, 23, 24, 25, 26, 27, 28, 29 and 30 therebetween, all of said pockets communicating with a central chamber or pocket 32 where an oxide coated nickel base cathode 33 is positioned.

The coaxial terminal or output lead 34, in the present embodiment, is shown positioned by having its inner end portion curved or looped back on itself and connected to the inner peripheral portion of the housing member, as indicated at 35. In the present instance the terminal member 34 has its large and tapering portions formed of tungsten and its small or inner portion formed of electrolytic copper, and is enclosed in a tubular copper casing 36 having an annular flange 37 threaded as indicated at 38 for a coaxial capacitive cable coupling, which may correspond with the threaded portion 24 of the Rigrod et al. patent, No. 2,408,271, dated Sept. 24, 1946. This casing is desirably threadably connected to the cylindrical portion 12 as indicated at 39.

The terminal 34 is desirably centered with respect to the casing 36 as by means of a Corning #704 or soft borosilicate glass bead 41 between the same and a cylindrical conductor member 42 which may be formed of "Kovar" (which is an alloy containing 28.7 to 29.2% nickel, 17.3 to 17.8% cobalt, 52.9 to 53.4% iron, not more than .06% carbon, not more than .5% manganese, and not more than .2% silicon) or other suitable material. The inner end of this conductor member 42 is desirably connected by eutectic gold-copper

solder to a steel ring 43 and the combination secured to the flange portion 37 by "BT" solder, as shown most clearly in Fig. 1. "BT" solder melts at about 779° C. and is 72% silver and 28% copper.

The cathode 33 in the present embodiment is shown as consisting of a helical tungsten filament 44 enclosed in an electron-emitting housing 45 composed of a mixture of oxides of strontium, barium and calcium on a nickel sleeve and supplied with power from a suitable source by tungsten leads 46 and 47. These leads project through copper casings 48 and 49, held in place as described in connection with the Okress application, Serial No. 460,376, previously referred to, which also shows how the power may be supplied to the cathode including the use of filters.

Figs. 3 and 4 show the blanks which are desirably employed to make the magnetron body during the process of manufacture. After the design, we desirably start with a plurality of plates 51, desirably of uniform thickness and numerically corresponding with the pockets, in this instance eight. These plates are desirably formed of selenium copper alloy or other similar metal, and are relatively thin although sufficiently heavy to provide a rugged construction.

We then take a shell portion 52 which is generally cylindrical on its exterior, but relatively thinned toward its ends as indicated at 53 and 54, to leave an inwardly extending annular boss 55. This boss is, in turn, slotted or grooved longitudinally or parallel to the axis, as indicated at 56 to a width so as to snugly receive the plates 51 and leave inwardly extending sections 57, numerically corresponding with the number of pockets desired in the finished magnetron, in this instance eight. The plates 51 are then fitted in the slots 56, as by means of a jig, and soldered in place as indicated at 58. This soldering is desirably effected with the use of "BT" solder or the like which is run into the space between the outer edge portions of the plates 51 and the receiving grooves or notches 56. Such soldering is desirably effected when the body is brought to the melting temperature of the solder in a protective atmosphere as in a hydrogen furnace.

After the plates 51, the cathode and its connections, and the terminal 34, are secured in place the body may be closed, as by connecting the upper and lower copper cover members 59 and 61 to the body, as shown in Fig. 2, with "RT" solder applied at the joints. "RT" solder melts at about 682° C. and is 60% silver, 25% copper, and 15% zinc. The whole assembly may be exposed in a hydrogen furnace and brought to the melting temperature of the solder, that is not high enough to melt the interior "BT" soldered connections, in order to effect such a union.

Referring now to the embodiment of our invention illustrated in Fig. 5, there is shown a magnetron 11^a consisting of a body or anode portion 12^a which, like the magnetron 11, is desirably formed of copper and has selenium copper alloy partitions, like the partitions of the preceding embodiment, only those numbered 15^a, 16^a, 17^a, and 18^a being shown, projecting inwardly from the peripheral portion 22^a and separated by pockets like those of the preceding embodiment, only those pockets numbered 25^a, 26^a, 27^a and 28^a being shown. All of these pockets communicate with a central chamber 32^a where a cathode may be positioned as in the first embodiment.

In the present embodiment, the housing or anode member 12^a is formed by taking a plain

hollow cylinder and connecting radially projecting partition wall members in place by means of "BT" solder, indicated at 58^a, said plates being desirably held with their outer edges, as by means of a jig, in abutting engagement with the inner surface of the cylindrical outer member 22^a, while in a hydrogen furnace where the soldering is effected, as in the preceding embodiment.

In the present embodiment we have shown an alternative terminal 34^a which, like the terminal 35 of the Okress application, Serial No. 460,376, previously referred to, has large and tapering portions desirably formed of tungsten and a small or inner portion formed of electrolytic copper and enclosed in a tubular copper casing 36^a corresponding with the casing 36 of the preceding embodiment, and centered with respect thereto in a similar manner.

In the present embodiment, however, the inner portion of the terminal 34^a, instead of being bent back on itself and connected to the outer cylindrical portion of the housing, extends to one of the partition plates, such as that designated 15^a, passing into a recess 35^a thereof, and secured thereto in any desired manner, as by means of "BT" solder. It will be noted that such a coupling may be used in the preceding embodiment, or that of the preceding embodiment used in this embodiment, interchangeably, within the spirit and scope of our invention.

In both embodiments of our invention the portions 13, 14, etc. or 15^a, 16^a, etc. projecting inwardly from the peripheral portion 22 or 22^a are all generally thin and of uniform thickness, like the slots 23 to 29, inclusive and 31 of the first embodiment of the Okress application, Serial No. 460,376, previously referred to, that is, the slots or pockets therebetween are generally triangular, trapezoidal, or sector shaped in section. In all the embodiments, however, the inner circumferential width of each pocket is uniform and may correspond with the uniform circumferential width of the separating partitions, notwithstanding the variation in outer circumferential width of these parts, although this correspondence is not essential.

Magnetrons with sector shaped pockets, like those of the present invention, are of lighter weight and have greater efficiency and power capacity than those with slotted pockets, relatively narrow, as illustrated in Fig. 1 of said Okress application, Serial No. 460,376, previously referred to. This is because the impedance of the generally triangular, trapezoidal or sector shaped slot or pocket at the slot aperture is much higher than that of the slot of uniform width, and hence such a pocket shape results in a much better match for the electronic field impedance than in the case of a magnetron with thin slots of uniform width. The wavelength sensitivity for pockets of the present embodiment, with regard to their structural parameters, is between that of the rectangular or thin slot and the conventional cylindrical cavity structure previously referred to.

From the foregoing, it will be seen that we have provided an improved magnetron and method of manufacture which avoids the necessity of accurate machining, simplifies and cheapens the construction, increases the permissive tolerances, and economizes in the use of material.

Although preferred embodiments of our invention have been disclosed, it will be understood that modifications may be made within the spirit and scope of the appended claims.

We claim:

1. A magnetron housing formed as an outer generally cylindrical hollow conductive portion having longitudinal grooves from which flat sided partitions project inwardly defining a central cathode cavity communicating with chambers generally sector shaped in section on a plane perpendicular to the axis and disposed thereabout, a cathode assembly disposed in said cavity, leads from said cathode assembly projecting through 10 said hollow cylindrical portion to outside of said housing, an output lead extending into said housing in a generally radial direction, curved backward and united to the inner surface of said housing, and a conductor casing in contact with and projecting from said housing and disposed coaxial with respect to said lead.

2. A magnetron housing comprising a hollow cylindrical portion of oxygen-free high-conductivity copper from which parallel-sided walls of 20 selenium copper alloy project inward in generally radial directions defining a central cavity communicating with pockets disposed therearound, the outer edge portions of said walls fitting in grooves in said cylindrical portion and secured 25 in place by solder.

3. A magnetron comprising a cathode and a hollow cylindrical conductive portion housing said cathode, a plurality of parallel-sided walls of conductive material different from that of said 30 cylindrical conductive portion encircled thereby axially shorter than said cylindrical portion, and projecting from the inner surface thereof in generally radial directions defining a central cathode cavity communicating with pockets disposed 35 therearound, the outer edge portions of said walls fitting in grooves in the inner surface of said hollow conductive portion and held in place by solder, and cover members secured to the parts of said cylindrical portion which project axially beyond said walls.

4. An electron-discharge device comprising: a cathode; and an anode structure spaced from and

surrounding said cathode and including a plurality of anode members, each pair of adjacent anode members comprising vanes secured in inwardly opening slots in a peripheral portion of said structure, thereby defining therewith a cavity resonator, said vanes having substantially straight side walls defining cavities expanding for an appreciable distance between the inner and outer ends thereof, leads from said cathode projecting through said anode structure to outside of said device, an output lead extending into said structure in a generally radial direction, curved backward and united to the inner surface of the outer portion of said structure, and a conductor casing in contact with and projecting outwardly from said outer portion and disposed coaxial with respect to said lead.
